UNITED STATES PATENT OFFICE

153,977

DESIGN FOR A GAS RANGE

Harry L. Porter, Cincinnati, Ohio, assignor to
Noma Electric Corporation, New York, N. Y., a
corporation of Maryland

Application July 9, 1947, Serial No. 140,168

Term of patent 7 years

(Cl. D81—4)

To all whom it may concern:

Be it known that I, Harry L. Porter, a citizen of the United States of America, residing at Cincinnati, in the county of Hamilton and State of Ohio, have invented a new, original, and ornamental Design for Gas Range, of which the following is a specification, reference being had to the accompanying drawing, forming a part thereof.

In the drawing, the single figure is a perspective view of a gas range showing my new design, the opposite side of the range being the same as that shown, the right-hand removable cover being shown in place and the left-hand removable cover being shown raised.

I claim:

The ornamental design for a gas range, substantially as shown and described.

HARRY L. PORTER.
